UNITED STATES PATENT OFFICE.

JOHN FREEMAN, OF NEW YORK, N. Y., ASSIGNOR TO SAVE-A-ROOM FURNITURE MANUFACTURING COMPANY, INC., OF NEW YORK, N. Y., A CORPORATION OF DELAWARE.

CONVERTIBLE FURNITURE.

1,381,293.

Specification of Letters Patent. Patented June 14, 1921.

Application filed April 17, 1920. Serial No. 374,591.

To all whom it may concern:

Be it known that I, JOHN FREEMAN, a citizen of the United States, residing at 2 East 181st street, New York city, in the 5 county of Bronx, State of New York, have invented certain new and useful Improvements in Convertible Furniture; and I do hereby declare the following to be a full, clear, and exact description of the invention, such as will enable others skilled in the art to which it appertains to make and use the same.

The present invention relates to convertible furniture and particularly to couches, 15 sofas, cots and similar furniture which may be converted from day furniture into beds or the like, and, by simple and efficient means, enlarged as from single to double width.

20 Heretofore, in furniture capable of being converted from day to night use, it has been the practice to extend the length or width by means of folding sections hinged at adjacent edges, or to lower the back to form 25 one of the mattress sections, or to slide the extensible section from underneath the fixed section. In these constructions considerable physical effort is required to convert the furniture, and often, in the case of beds, either 30 the mechanism is complicated or the two sections do not lie in the same plane when opened out. In some cases, also, two people are required to convert it, and sometimes 35 the furniture must be pulled away from the wall for opening it out.

In accordance with one part of my invention, the convertible furniture, whether folding or otherwise, comprises a combined reversible base section and a collapsible section, 40 said collapsible section arranged to be superimposed upon the base section for compactness and sightlessness in day use, and opened out in juxtaposition to and in substantially the same plane with the base section to produce a double width bed comparable in comfort and appearance with the ordinary bed, the combined base and collapsible sections being provided with a novel reversing means and said sections connected 45 by mechanism which is constructed and arranged to assist the raising movement or retard the falling movement, or both, when the collapsible section is changed from one position of rest, that is, superposed upon

the base section, to the other position of rest, that is, fully opened out from the base section. In the specific embodiments hereinafter disclosed, the mechanism connecting the sections includes at each end spring-actuated link mechanism comprising a pair 55 of links and a spring connected thereto so as to be stressed when the collapsible section is in either position of rest, thereby materially reducing the physical effort required to change the position of the collapsible section from either position of rest 60 to the other.

In the accompanying drawings illustrating the invention in application, as an example, to two forms of couch beds in which 70 a collapsible section is guided in movements of substantial parallel translation with the assistance of a spring and connecting mechanism at each end to a juxtaposed position in substantially the same plane with the 75 base section to form a double width bed.

Figure 1 is a perspective view of a reversible couch bed with a back converted for day use as a couch; Fig. 2 is a perspective view thereof in reversed position, showing the frame work of the head pieces or arms in lowered position, and showing, in broken lines, the collapsible section opened out; Fig. 3 shows the base and collapsible sections thereof in two positions during reversal; Fig. 4 is a section on line 4-4 of Fig. 3; Fig. 5 is an enlarged fragmentary end view of the section opened out; Fig. 6 is a perspective view of a form of couch bed, without a back, in which the base section 80 is stationarily supported on legs; Fig. 7 is similar to Fig. 6 but shows the collapsible section partly opened out; Fig. 8 is similar to Fig. 6 but shows the collapsible section 85 fully opened out; Fig. 9 is an enlarged fragmentary end view of the sections opened out; and Fig. 10 is a section on line 10-10 of Fig. 9.

In both embodiments, the base section 1 and the collapsible section 2 each consist of 100 frames having longitudinal angle irons 3 and end angle irons 4 joined together. These sections are connected at their respective ends by mechanism comprising bell crank levers 5 journaled on pivot pins 6 105 near the inner corners of the collapsible section, and on pivot pins 7 near the median line of the base section; bell crank levers 8

journaled on pivot pins 9 near the outer corners of the base section and on pivot pins 10 near the median line of the collapsible section; and springs 11 secured to the 5 bell crank arms 12 and 13 of the levers 5 and 8. When the collapsible section 2 is superimposed upon the base section 1, or when opened out in juxtaposition thereto, the levers 5 and 8 are in an inclined position 10 in which the distance between the ends of the bell crank arms 12 and 13 is greatest, thus stressing springs 11 and tending through the levers 5 and 8 to assist in raising the collapsible section from either position 15 of rest and opposing its fall to the base section or to the floor. During these changes of position, the levers 5 and 8 guide the collapsible section in movements of translation, or more specifically in movements 20 of substantial parallel translation, the collapsible section moving bodily in a substantially vertical direction in initially rising from and finally descending to either position of rest. This movement permits 25 the furniture to stand closely against the wall, and also makes it possible to fasten the supporting legs 14 permanently and rigidly to the collapsible section without interfering with the closing of the latter upon 30 the base section in superimposed relation, or reversing the base and collapsible sections even when the couch bed has a back. Supporting brackets 15 are riveted to the end angle irons 4 of the base section to receive 35 the levers 5 and support the inner end of the collapsible section when opened out. (See Figs. 4, 5, 9 and 10.)

In the embodiment of Figs. 1 to 5, the base and collapsible sections are, when in 40 superimposed relation, reversible on the base of the couch, and are adapted to be seated thereon with either side uppermost, substantially as disclosed in my copending application Serial No. 297,056 filed May 14, 1919. 45 The base of the couch consists of an open rectangular frame of wood having longitudinal stringers 16, cross pieces 17, end-supporting rails 18, and legs 19. Hinged to the ends of the base of the couch are head pieces 50 or arms 20, which may be raised and lowered by any suitable mechanism, as for instance the mechanism forming the subject matter of my Letters Patent No. 1,334,365 issued March 23, 1920. The base section 1 carries 55 end-supporting members 21 which, together with the end rails 18, provide a sliding pivotal connection between the base section 1 and the base of the couch. The reversing mechanism connecting each end of the base 60 section to the base of the couch consists of pairs of links 22 and 23, one pivoted to the end-supporting members 21 at 24, and the other to the base of the couch at 25, the springs 26 being connected between the links 65 23 and the base of the couch to assist

in raising the base and collapsible sections for reversing them, and to oppose their fall after reversal. (See Fig. 3.)

The end-supporting members 21, connected to the base section 1 by bolts 27, are offset by spacing sleeves 28 and blocks 29, and are recessed at 30, to provide clearance for the free movement of the levers 5 and 8. (See Fig. 4.) A guide plate 31 is riveted 75 in the recess 30 of the end-supporting members 21 and engages the inside of the end-supporting rails 18 to prevent lateral displacement of the links and levers during the reversing and converting movements. To further support the collapsible section, a strip of wood 32 is fastened to the under side 80 of the base section at the outer edge thereof adjacent the collapsible section when the latter is opened out to form a ledge upon which the inner edge of the collapsible section 85 rests. (See Fig. 5.)

Fastened in the frame of each section is a flat wire spring (not shown) which serves in the base section as a resilient support for the upholstered cushions 33 on top thereof, 90 and for the mattress 34 on the bottom, and in the collapsible section as a resilient support for the mattress 35. The base and collapsible sections are held together during the reversing movements by a strap 36 secured to the frame of the base section. Pivoted near the ends of the collapsible section are pillow-supporting frames 37 which may be swung down upon the mattress 35, to hold the mattress 35 in position when the sections 100 are reversed. When either frame 37 is released from the latch 38 for the holding spring 39 and thrown up to the position shown in broken lines in Fig. 2 against the stop 40, it serves to support the pillows for 105 night use.

To reverse the couch bed from day to night use or vice versa, it is merely necessary to give the reversible unit, comprising the base and collapsible sections, an upward pull from the front of the couch, whereupon the pivot pins 24 are guided upwardly by the links 22, 23 upon combined actions of the operator and the springs 26, and the reversible unit is guided by the end-supporting members 21 sliding and rolling on the rails 18 as indicated in Fig. 3. When the reversible unit falls, its downward movement is opposed by the springs 26 as they become stressed. Neither the back 41 nor the legs 120 14 interfere with the reversing movement and the head pieces or arms 20 may be lowered, if desired, to an adjusted position before or afterward. When the reversible unit is in the position shown in Fig. 2, the 125 device may be used as a single width bed, or the collapsible section may be moved to the broken line position in juxtaposition to and in substantially the same plane with the base section by first unfastening the strap 130

36 and then pulling the collapsible section forward from the front by means of the handle 42, the collapsible section initially rising and finally falling in a substantially 5 vertical direction and passing through the intermediate position shown in Fig. 7 in movements of substantial parallel translation. The springs 11 are stressed when the collapsible section is in either position of 10 rest. In assisting the operator at the beginning of the movement from either position and retarding the falling movement to the other position, by passing through an unstressed condition in the intermediate position 15 (illustrated in Fig. 7), the springs materially reduce the physical effort required and reduce the shock and noise.

In the embodiment shown in Figs. 6 to 10, the base section 1 is stationarily supported 20 on the legs 43. Since the sections do not reverse, the strap 36 and, if desired, the pillow-supporting frames 37 of the first embodiment may be omitted. To further simplify the construction, the ledge 32 of the 25 first embodiment may be omitted, the collapsible section, when extended, being supported by the legs 14 and the brackets 15 receiving the links 5. The sections have flat 30 mattresses 44 and 45 are placed thereon.

The collapsible section 2 is provided with a handle 46 and moves from the superimposed position shown in Fig. 6 to the extended position shown in Fig. 8, and vice versa, 35 through the intermediate position shown in Fig. 7, in the same way as previously described with respect to the first embodiment. A cover over the device when the collapsible section is superimposed on the base section 40 renders it slightly and useful for day use.

Having thus described my invention, what I claim is:

1. In convertible furniture, a base section, a collapsible section adapted to be superimposed upon and opened out in juxtaposition to and in substantially the same plane with said base section, and pairs of bell crank levers connected to pivotal points on 45 respective ends of said base and collapsible sections to guide said collapsible section, relative to said base section, in movements of parallel translation when the position of said collapsible section is changed, and a 50 spring connected to said bell crank levers to assist the raising movement and to retard the falling movement during the change of position.

2. In convertible furniture, a base section, 55 a collapsible section arranged to be superimposed upon and opened out in juxtaposition to and in substantially the same plane with the base section, and a support for the collapsible section when opened out comprising a ledge which is carried by the base sec-

tion and upon which the collapsible section rests and links connected to pivotal points near each inner corner of the collapsible section and brackets carried by the base section near the outer corners thereof for supporting said links. 70

3. In convertible furniture, a base section, a collapsible section arranged to be superimposed upon and opened out in juxtaposition to and in substantially the same plane 75 with the base section, an end supporting member on said base section, a link connected to pivotal points on the base and collapsible sections, a recess in said end supporting member to permit said link to move 80 freely to the inner inclined position when the collapsible section is superimposed upon the base section and to the outer inclined position when the collapsible section is opened out, and a guide in said recess arranged to 85 preclude the lateral movement of the sections throughout the change from one position to the other.

4. In convertible furniture, a reversible body comprising a combined main section 90 and collapsible section, said collapsible section adapted to be superimposed upon and opened out in juxtaposition to and in substantially the same plane with said main section, pairs of bell crank levers connected 95 to pivotal points on respective ends of said main and collapsible sections to guide said collapsible section, relative to said main section, in movements of parallel translation when the position of said collapsible section 100 is changed, and a spring connected to said bell crank levers to assist the raising movement and to retard the falling movement during the changing of position.

5. In convertible furniture, a reversible 105 body, comprising a combined main section and collapsible section, said collapsible section adapted to be superimposed upon and opened out in juxtaposition to and in substantially the same plane with the main 110 section, a support for the collapsible section when opened out comprising a ledge which is carried by the base section and upon which the collapsible section rests and links connected to pivotal points near each inner corner 115 of the collapsible section and brackets carried by the base section near the outer corners thereof for supporting said links.

6. In convertible furniture, a supporting base, a reversible body adapted to be seated 120 on said base with either side uppermost, said body comprising a main section and an extensible and collapsible section, double-ended supporting members carried by the body at its respective ends to form moving fulcrums, 125 vertically movable pivot connections between the base and the body, and springs assisting in the elevation of the vertically movable pivot connections during the movement of the fulcrums in one direction and oppos- 130

4
ing the fall of the vertically movable pivot connections during the movement of the fulcrums in the other direction as the body is turned for reversing.

5 7. In convertible furniture, a supporting base, a reversible body adapted to be seated on said base with either side uppermost, said body comprising a main section and an extensible and collapsible section, a double-ended moving fulcrum between the base and the body, pivots carried by the body at its respective ends, a plurality of links connected to each of the pivots and the base, springs connected between the base and the links so 10
15 as to tend to raise the body from the base

during the movement of the fulcrum in one direction and to oppose the fall of the body to the base during the movement of the fulcrum in the other direction as the body is turned for reversing, pairs of bell crank 20 levers connected to pivotal points on respective ends of said main section and collapsible section for extending said collapsible section, and a spring connected to said bell crank levers to assist the raising movement 25 and to retard the falling movement of said collapsible section during the changing of position.

In testimony whereof I affix my signature.
JOHN FREEMAN.
